UNITED STATES PATENT OFFICE.

JAMES PAULL, OF WELLSBURG, WEST VIRGINIA, ASSIGNOR TO EAGLE GLASS & MANUFACTURING COMPANY, OF WELLSBURG, WEST VIRGINIA, A CORPORATION OF WEST VIRGINIA.

DESIGN FOR A MOLASSES-JUG.

42,647.

Specification for Design.

Patented June 18, 1912.

Application filed February 24, 1912. Serial No. 679,629. Term of patent 14 years.

To all whom it may concern:

Be it known that I, JAMES PAULL, a resident of Wellsburg, in the county of Brooke and State of West Virginia, have invented a new, original, and ornamental Design for Molasses-Jugs, of which the following is a specification, reference being had to the accompanying drawings, forming part thereof, in which the figure is a perspective view of a molasses-jug, showing my new design.

Prominent features of my design consist in the vertical reentrant recesses separating adjacent panels of the body portion of the jug; the distinct outward swell at the lower portion of the jug; the panels extending down to form a part of the swell and the aforesaid reentrant recesses continuing into the swell; the upward inclination of the top of the nose of the jug; the sub-

stantially flat cover portion having an upturned lid member covering the nose; the upturned finger press at its extreme rear edge and over the handle; and the hinge lugs forming a part of this finger press and extending down to a band member which lies within an annular groove at the upper portion of the body, the band member embracing only about one-half the circumference of the top of the jug.

I claim:

The ornamental design for a molasses jug, as shown and described.

In testimony whereof, I have hereunto set my hand.

JAMES PAULL.
